COIN SELECTOR

Christian Gabrielsen, Mountain Lakes, N. J., and
 Jules Nisenson, New York, N. Y., assignors to
 Rowe Manufacturing Co., Inc., New York, N. Y.,
 a corporation of New York

Application December 6, 1944, Serial No. 566,798

5 Claims. (Cl. 194—102)

1

This invention relates to improvements in vending machines and more particularly in coin sorting devices for such machines.

The general object of the invention is to provide improved means for sorting coins of different denominations.

With this and still other objects which will appear in the following full description in mind, the invention consists in the combinations, arrangements of parts and details of construction, which will now first be fully described in connection with the accompanying drawing, and then be more particularly pointed out in the appended claims.

In the drawing:

Figure 1 is a side elevation of the upper part of a coin selector embodying the invention in a preferred form.

Figure 2 is a view similar to Figure 1 but with certain parts removed to show the internal mechanism.

Figure 3 is a section taken on the line 3—3 of Figure 2.

Figure 4 is a detail view taken on the line 4—4 of Figure 1; and

Figure 5 is a detail view taken on the line 5—5 of Figure 1.

In the drawing, there is shown only the upper part of the coin selector, it being understood that the complete coin selector embodies additional structure together with suitable coin guiding, testing or registering mechanism such, for example, as shown in the previous Gabrielsen Patent No. 2,286,614. The device of the present invention is intended to provide for the rapid sorting of coins of different denominations, such as quarters, nickels and dimes, which are inserted in the machine through a common slot 1, as indicated in Figure 2, and comprises a plate 2 serving as the general supporting structure and on which are carried the various testing, guiding and sorting devices. As best shown in Figure 1, cover plate 3 is pivotally supported on a shaft 4 which is carried in bearings at 5 and 6 by the support plate 2. The coil spring 7 serves to urge the plate into the position of Figures 1 and 3. The plate 3 also carries the projection 8 cooperating with vertically slidable member 9 so that upward movement of this member swings the plate 3 outwardly for stripping coins or slugs. This operating structure, being similar to that shown in the previous Gabrielsen Patent No. 2,286,614 and forming in itself no part of the present invention, requires no further description. The plate 3 is formed with apertures 10 and 11 to accommodate two

2

magnets 12 and 13 which are fastened to support plate 2 and with a further aperture 14 to permit movement of the coins, as later described, and also carries the member 15 (Figure 2) which defines, together with the plates 2 and 3, certain coin passageways, as later described in detail.

The upper surface 16 of member 15 forms the bottom of a passageway down which coins inserted in the slot 1 roll by gravity. In so rolling, 10 the coins pass through the field of magnet 12 which serves to stop paramagnetic slugs. Such slugs are removed from the device by the stripping arm 17 pivotally carried at 18 on the support plate 2 and actuated by the member 9. As will be understood, as the member 9 is moved upwardly, plate 3 swings outwardly carrying with it the member 15 and leaving any slug held by the magnet 12 unsupported. The arm 17, swinging downwardly, pushes the slug out of the field of magnet 12 so that it falls upon the beveled upper surface of deflector member 19 and is directed into a passageway for returns or rejects. Coins which pass the magnet 12 continue to roll down the incline 16 and are sorted according to size. 15 To accomplish this purpose, the support plate 2 carries a pair of deflecting members 20 and 21 and each of which comprises an inclined forward portion 20a or 21a and rearward stops 20b or 21b. Adjacent the members 20 and 21, 20 the plate 2 is formed with apertures 22 and 23 having upper edges 24 and 25 which are beveled or slanted away from the support plate 3 and lower edges 26 and 27 which are slanted toward the plate 3. As will be observed, the upper edges 25 of both of these apertures, which form the entrances for the coin passages 22, 32 and 23, 33, are positioned above the incline 16 by less than the diameter of the smallest coin used, which, in this case, is a dime. On the opposite side from 25 plate 3, there is affixed to support plate 2 a member 28 comprising an upper portion forming a coin receiving hopper 29 for the apertures 22 and 23, the hopper serving to receive any coin deflected out from the incline 16 and to guide 30 the same into the opening 22 or 23 as the case may be. Coins so deflected will be carried from openings 22 and 23 onto the respective inclines 30 and 31 from whence they proceed into the quarter passage 32, or nickel passage 33. A dime, 35 being of insufficient diameter to engage either member 21 or 20, will roll down the incline into the dime passageway 34 as indicated.

As just stated, a dime, since it engages neither of the members 20 and 21, will roll all the way 55 down the incline 16 into the dime passageway.

A nickel will be of insufficient diameter to engage the member 20 but will engage the member 21. When it so engages, it will be deflected outwardly, causing it to fall off the incline 16, whereupon it enters the opening 23 and is guided onto the incline 31 so that it passes into the nickel passageway 33. A quarter will similarly be deflected into the passageway 32 by the member 20.

Within the limits of the coin passageway above the incline 16, the members 20 and 21 are beveled, as best shown in Figure 4 and the stops 20b and 21b extend outwardly into the space for accommodating tilted coins which is created by the bent portion 35 of the plate 3. Accordingly, the action of each of the members 20 and 21 is to urge the upper part of the coin outwardly and the portion 35 serves as a fulcrum, so that the result is to urge the lower part of the coin in the opposite direction and positively deflect it into the opening 22 or 23, as the case may be. The portions 20a and 21a of the members 20 and 21, in addition to being slanted in a direction parallel to the surface 16, are also beveled downwardly as shown in Figure 5. In this way, the turning movement of the coin is effected smoothly and continuously without any possibility of binding. Slugs of diameters other than the coins referred to may, however, be stopped and held in the machine by the members 20 and 21, due to their inability to pass into the openings 22 or 23. Where this occurs, they will be dropped off when the member 9 is actuated to open the plate 3 and will be rejected.

As will be observed, a means has been provided by means of which the coins are sorted into their proper passages without any slowing down and with the full velocity of the coins being preserved and utilized to effect the sorting. In this way, the sorting of coins from a common slot is accomplished by very simple mechanism without slowing the operation of the machine.

What is claimed is:

1. Coin sorting mechanism comprising, in combination, a runway for coins to be sorted, a coin deflector in said runway, spaced from the bottom thereof to engage coins of given diameter but not coins of lesser diameter and having a coin engaging portion slanting outwardly from one wall of said runway in the direction of travel of coins therealong, the said wall having an opening below said deflector for discharging a coin laterally from said runway, a fulcrum opposite said coin deflector and below said coin engaging portion for cooperating therewith to tilt coins so that their lower portions are forced laterally under said deflector, and into said opening and a coin receiving passageway alongside said runway and communicating with said opening below said deflector for receiving coins deflected thereby.

2. Coin sorting mechanism comprising, in combination, a runway for coins to be sorted comprising a floor and members defining side walls, a coin deflector in said runway, spaced from the floor thereof to engage coins of given diameter but not coins of lesser diameter and having a coin engaging portion slanting across said runway in the direction of coin travel, a passageway alongside said runway and extending through one of the said side wall members adjacent said deflector to form in said wall an opening below said deflector for receiving coins deflected there-

by, and the other said side wall member having a fulcrum for urging the lower portion of a coin engaged by said deflector off the said floor and into said opening below said deflector for deflecting the coin into said passageway.

3. Coin sorting mechanism comprising, in combination, a runway for coins to be sorted, a coin deflector in said runway, spaced from the bottom thereof to engage coins of given diameter but not coins of lesser diameter and having a coin engaging portion slanting outwardly from one wall of said runway in the direction of travel of coins therealong, the said wall having an opening below said deflector for discharging a coin laterally from said runway and a stop beyond said slanting portion, a fulcrum opposite said coin deflector and below said coin engaging portion for tilting coins under said deflector and into said opening, and a coin receiving passageway alongside said runway and communicating with said opening below said deflector for receiving coins deflected into said opening.

4. Coin sorting mechanism comprising in combination, a runway for coins to be sorted, means for tilting coins laterally out of said runway comprising a coin deflector in said runway and spaced from the bottom thereof to engage coins of given diameter but not coins of lesser diameter and means cooperating with said deflector for tilting the lower part of the coin laterally, and a passageway alongside said runway having an entrance from said runway through the runway wall below said deflector for receiving coins deflected thereby and the top of the said entrance being spaced from the bottom of the said runway by a distance less than the diameter of coins of said lesser diameter.

5. Coin sorting mechanism comprising, in combination, a runway for coins to be sorted, a coin deflector in said runway, spaced from the bottom thereof to engage coins of given diameter but not coins of lesser diameter and having a coin engaging portion slanting outwardly from one wall of said runway in the direction of travel of coins therealong, a fulcrum in the other wall of the runway opposite said coin deflector and below said coin engaging portion for tilting coins under said deflector, and a coin receiving passageway alongside said runway having an entrance from said runway through the first mentioned wall below said deflector for receiving coins deflected thereby and the top of the said entrance being spaced from the bottom of the said runway by a distance less than the diameter of coins of said lesser diameter.
